UNITED STATES PATENT OFFICE.

CHARLES W. MENIGE, OF PHILADELPHIA, PENNSYLVANIA.

HYDRANT.

1,316,799.

Specification of Letters Patent. Patented Sept. 23, 1919.

Application filed March 6, 1919. Serial No. 281,095.

To all whom it may concern:

Be it known that I, CHARLES W. MENIGE, a citizen of the United States, residing at Philadelphia, in the county of Philadelphia 5 and State of Pennsylvania, have invented certain new and useful Improvements in Hydrants, of which the following is a specification.

One object of my invention is to provide 10 an improved hydrant which will include a stop and waste cock or valve operative to shut off the flow of water through the hydrant when the cock is turned off and at the same time drain the hydrant to prevent 15 freezing.

Another object is to make the parts of my improved hydrant of such construction that they can be easily made, assembled, and taken apart.

20 A still further object is to so construct my improved hydrant that access may be easily had to the valve mechanism either for the purpose of cleaning, repair or replacement.

25 Another object is to make my invention of such construction that it will be durable and efficient when a part thereof is under ground and as such will be advantageous when used as a fire hydrant for use in the 30 streets of cities, towns, etc.

These objects, and other advantageous ends which will be described hereinafter, I attain in the following manner, reference being had to the accompanying drawings 35 in which—

Figure 1 is an outside elevation of my improved hydrant showing a portion thereof embedded in the ground,

Fig. 2 is an enlarged sectional view of my 40 improved hydrant,

Fig. 3 is a fragmentary top plan view of Fig. 2,

Fig. 4 is a side elevation of Fig. 3,

Fig. 5 is a section taken on the line 5—5 45 of Fig. 2, and

Fig. 6 is a fragmentary section taken on the line 6—6 of Fig. 5.

Referring to the drawings, 7 represents a standard in the form of a metallic pipe 50 which is externally screw threaded at its opposite ends and may be of any desired length. The lower portion of the standard 7 is adapted to be embedded within the ground as shown at 8 in Fig. 1 and at its 55 lower end has a valve casing 9 screwed

thereon. This valve casing 9 has a substantially conical body portion 10 and a branch 11. A water inlet passage 12 extends through the branch 11 and a water main 13 is coupled to the branch 11 by a coupling 60 14, so that said water main will supply water to the inlet passage 12. The valve casing 9 has a downwardly tapering conical bore 15 with which the inlet passage 12 transversely communicates. A frusto-conical 65 ground valve 16 fits within the conical bore 15 and is adapted to cut off the inlet passage 12. The valve 16 is of such size that it does not extend entirely to the bottom of the bore 15. On the contrary, a space 17 is provided between the bottom of the valve 16 and the bottom of the bore 15. I preferably place grease in the space 17 and provide the valve 16 with a groove 18 in its outer surface, said groove 18 connecting with the 70 space or grease well 17 to permit the grease to move upwardly into engagement with the portion of the surface of the bore 15 with which the valve 16 contacts. Thus provision is made to lubricate the ground valve 16. 80

The valve 16 has a chamber 19 within its length and an inlet port 20 communicates with said chamber and is also positioned when the valve 16 is turned, to register with the inlet passage 12 to permit water to enter 85 the chamber 19. The chamber 19 has an outlet port 21 which extends entirely through the valve 16 above the conical bore 15. The standard 7 is of greater internal 90 diameter than the external diameter of the top of the valve 16 and thus the water passing into the chamber 19 will pass out of the port 21 and then upwardly through the standard 7.

The upper end of the standard 7 has a 95 sleeve 22 screwed thereon, said sleeve having a branch 23. The branch 23 is internally screw threaded and communicates with the sleeve 22 and interior of the standard 7. A nozzle 24 is screwed within the branch 100 23 and can if desired be used for dispensing the water directly or by attachment of a hose. The sleeve 22 and branch 23 is in the form of a T-fitting and can be of any desired size according to the requirements of 105 the hydrant.

A cap or head 25 is screwed on the top of the sleeve 22 and has an inner frusto-conical 110 upwardly tapering surface 26 which provides a seat for a frusto-conical valve 27.

The surface 26 extends entirely to the top surface of the cap 25 and the upper end of said valve 26, as illustrated, extends above the top of the cap 25. The valve 27 has a 5 stem 28 which is angular in cross section in the form of a nut and a hand lever 29 fits said stem and is secured thereto by a plate or washer 30 which projects over the parting between the stem and the lever; said plate 10 or washer 30 being secured to the stem 28 by a screw 31, as clearly shown in Figs. 2 and 3.

The valve 27 has a depending projection 15 32 provided with a cavity 33 which is angular in cross section and into which is adapted to slidably fit the upper end of a rod 34, said rod also being angular in cross section. A coiled cushion spring 35 is mounted within the cavity 33 and another coiled 20 spring 36 surrounds the projection 32 and rod 34 and is positioned between the bottom of the valve 27 and a washer or ring 37 which is held to the rod 34 by a pin 38.

The lower end of the rod 34 fits within 25 a groove 39 in the top of the valve 16. A pin 40 extends through the top of the valve 16 and also through the rod 34, thus locking the rod 34 to the valve 16.

By the above construction it will be noted 30 that the action of either or both of the springs 35 and 36 will serve to hold the valve 27 against its seat 26 and the valve 16 into engagement with the bore 15, thereby preventing leakage.

35 The body portion 10 of the valve casing 9 has a drain port 41 which is angularly disposed to the passage 12 and adapted to register with the port 20 when the valve 16 is in the position as shown in several views 40 of the drawing. The cap 25 is preferably provided with two lugs 42 and 43 which form means for limiting the turning movement of the lever 29, said lever also having a depending lug 44 adapted to engage both 45 of the lugs 42 and 43 when said lever is operated.

To operate the hydrant, the lever 29 is 50 swung so as to move the part 20 into register with the inlet passage 12. The water will then flow through the chamber 19, port 21, standard 7 and nozzle 24. To stop the hydrant, the lever 29 is moved into the position, as illustrated in the drawings, and any water confined in the hydrant will drain 55 downwardly through the standard 7, port 21, chamber 19, port 20, and drain port 41.

A hydrant made in accordance with my 60 invention as above described will withstand a great back pressure without leaking and for this reason it is well adapted for use as a fire hydrant, for hose connections or any other means where a great back pressure often occurs.

Furthermore, a hydrant made in accordance 65 with my invention can be readily taken

apart, it merely being necessary to remove the cap 25 when the entire valve structure can be removed; it being noted that to remove the valve 16 it is merely necessary to remove the rod 34, since said rod is locked to 70 the valve 16.

It will be noted that the sleeve 22 actually forms an extension and part of the standard 7, for the reason that it provides an extended casing communicating with the pipe which 75 forms a standard and through which the upper part of the rod 34 and projection 32 of the valve 27 extends.

While I have described my invention as taking a particular form, it will be understood 80 that the various parts of my invention may be changed without departing from the spirit thereof, and hence I do not limit myself to the precise construction set forth; but consider that I am at liberty to make 85 such changes and alterations as fairly come within the scope of the appended claims.

Having thus described my invention, what I claim as new and desire to secure by Letters Patent is:—

1. A hydrant including a valve casing having a valve seat; a valve in said casing; a hollow standard positioned to conduct fluid from said valve; a rod connected to said valve and extending through said standard; a cap on said standard providing a valve seat; a valve having a portion providing a slideway for said rod; and common resilient means for moving said valves into engagement with their seats; substantially 100 as described.

2. A hydrant including a valve casing; a valve in said casing; a hollow standard secured to said casing for conducting fluid from said valve; a rod connected to said valve and extending through said standard; means on the top of said standard providing a valve seat and having a hole therein; a valve adapted to engage said seat and slidably connected to said rod, said latter valve having a portion extending through said hole; an operating lever connected to said latter portion; and resilient means adapted to effect the sliding movement between said second valve and rod, whereby said latter valve is held against its seat and said first valve is held in fitting engagement with the valve casing; substantially as described.

3. A hydrant including a valve casing; a valve in said casing; a hollow standard secured to said casing and adapted to conduct said fluid from said valve; a rod connected to said valve and extending through said standard; a cap screwed on the top of said standard and providing a valve seat and having a hole therein; a valve adapted to engage said seat and slidably connected to said rod, said valve having a portion extending through said hole; an operating lever connected to said latter portion; and a spring

interposed between said second valve and a portion of said rod, whereby said first valve is held in engagement with the valve casing and said second valve is held in engagement with its seat to prevent leakage through the hole in said cap, substantially as described.

5 In testimony whereof I have signed my

name to this specification in the presence of two subscribing witnesses.

CHARLES W. MENIGE.
